UNITED STATES PATENT OFFICE.

EDWIN A. REEVES, OF MILFORD, CONNECTICUT.

APPARATUS FOR MIXING GAS AND AIR.

1,208,654.

Specification of Letters Patent.

Patented Dec. 12, 1916.

Application filed November 26, 1915. Serial No. 63,692.

To all whom it may concern:

Be it known that I, EDWIN A. REEVES, a citizen of the United States, residing at Milford, in the county of New Haven and State of Connecticut, have invented certain new and useful Improvements in Apparatus for Mixing Gas and Air, of which the following is a specification, reference being had therein to the accompanying drawings.

10 My invention relates to a new and improved apparatus for mixing gas and air, having for its object, among other things, to produce a device having this function wherein the relative proportions of gas and air may be predetermined and varied, irrespective of the pressure under which either the air or gas is admitted, and will also maintain the mixture in uniform proportions even though the pressure of the air or gas varies; and further, to so construct and arrange the several elements that differential friction between the several valves and their connecting mechanisms will be entirely eliminated, as well as any differential pressure between the air and gas diaphragms.

15

20

25

To these, and other ends, my invention consists in the improved apparatus for mixing gas and air, having certain details of construction and combinations of parts, as will be hereinafter described and more particularly pointed out in the claims.

Referring to the drawings, in which like numerals of reference designate like parts in the several figures; Figure 1 is a fragmentary side elevation of my improved apparatus complete; Fig. 2 is a fragmentary plan view thereof; Fig. 3 is a sectional view of the upper portion of the apparatus, taken upon line C—D of Fig. 2; Fig. 4 is a sectional plan view, taken upon line A—B of Fig. 1; Fig. 5 is an enlarged view of some of the parts, taken upon line E—F of Fig. 3; and Fig. 6 is a transverse sectional view of some of the parts, taken upon line G—H of Fig. 5.

In my apparatus the gas and air enter under any variable pressure, the air usually at atmospheric pressure, which in itself is variable within a limited range, and are united and delivered at an exit or exhaust point in predetermined proportions and at a uniform and constant pressure.

50 Heretofore it has been difficult to automatically proportion gas and air and such devices as have been designed to accomplish

this purpose have been complicated, costly, and for various other reasons, unsatisfactory in their operation and produce an unstable and variable product, so much so as to materially impair the usefulness and efficiency of the device. It has been common practice to successfully pump air and gas through a pipe into a reservoir where the air and gas are supposed to mix without the aid of mechanical devices, and thereafter in an assumed mixed condition the gas and air are conveyed to the point of consumption, assisted by a pump or similar means. Another method in more or less common use is to preliminarily change the pressure of either the gas or air or both so that it may enter the apparatus at a constant predetermined pressure; and still another method is to produce the desired result by the use of 75 ports or inlets with means for varying disproportionately the areas of said ports or inlets. This result is accomplished by mechanism that is extremely simple in design and construction, composed of comparatively few parts and can be produced and sold at the minimum cost.

The mechanism is designed and arranged so as to be practically automatic and operates without the intervention and assistance of 85 pistons, gears, and other similar devices commonly used in apparatus of this character heretofore made.

For purposes of illustration I will assume that the gas admitted into my apparatus is 90 the illuminating gas usually delivered in cities, through the ordinary city main, and the pressure will vary at different times during the day. In fact we can conclude that the pressure will not be constant, al 95 though, of course, if the pressure is in fact constant the device will operate equally as well.

One advantage of having a device capable of operating under a variable gas pressure 100 is the fact that it may be used without modification or alteration at any place where there is a gas supply.

Between my apparatus and the point of consumption a suction pump is utilized to 105 perform the double function of drawing air and gas through the apparatus and forcing it to a delivery point or point of consumption. This suction pump is provided with such by-pass or automatic valves as 110 will relieve excessive pressure and will nullify the suction action of the pump at a pre-

determined pressure. Such pump and automatic mechanism is not new or novel, as any one of numerous forms of pumps and mechanism may be utilized, all of which 5 are common in the art and readily procurable in the open market.

In the embodiment of the invention I provide a body member 1, which is divided by the partitions 2 and 3 into three compartments or chambers, severally designated 4, 5 and 6, the chamber 4 being the gas chamber, 5 the air chamber, and 6 the vacuum chamber. Within each of these chambers is a flexible diaphragm 7 of a form and construction common in the gas meter art. Through the partition 2 is an opening 8 in the interior of the adjacent diaphragms within the air and gas chambers, whereby the pressure within these two diaphragms 20 will always be equal. Air is admitted into said diaphragms through the port 87, during the expansion thereof, and exhausts therefrom during their contraction.

Within each of the chambers 4, 5 and 6 25 is a rock shaft, the same being severally designated 9, 10 and 11, and each is journaled at its lower end in a block 12, and at its upper end projects through the top of the body member and is journaled in a sleeve 13. Each rock shaft is connected with the adjacent diaphragm by an arm 14, which is secured at one end in a fixed relation to the shaft, and at the other end to the diaphragm by the pin 15 that passes through the posts 35 16 forming part thereof.

The lateral movement of the diaphragms, all of which are shown in their contracted relation, during their expansion and contraction, impart a rocking movement to the 40 shafts 9, 10 and 11, through the arms 14, as above described.

The numeral 17 designates the gallery member, which, by means of the partitions 18, 19 and 20, is divided into a plurality of 45 chambers severally designated as follows,— 21 the air chamber, 22 the gas chamber, 23 the exhaust chamber, 24 the gas inlet chamber, and 25 the air inlet chamber. The exhaust chamber 23 terminates in a cylindrical 50 neck portion 26, having a threaded head 27 thereon to provide convenient means for coupling a pipe thereon. The gas chamber 22 is connected with the exhaust chamber 23 by the port 28, and the air chamber 21 by the port 29. A branch 30 projects laterally 55 from the gallery member 17, is supported near its outer end by a standard 33, and opens into the gas inlet chamber 24 to provide means whereby a supply of gas is admitted into said chamber, and a similar branch 31 opens into the chamber 25 and provides means for admitting a supply of air thereto. The vacuum compartment 6 is connected with the exhaust chamber 23 60 through the pipes 32 and coupling 34 and

the gas chambers 22 and 4 by the pipes 35 and coupling 36, and the air chamber 21 with the air compartment 5 by means of the pipe 37 and coupling 33. Slidably mounted within the chamber 22, so as to cover and uncover the port 28, is the valve 38 and a similar valve 39 is provided in the air chamber 21 to cover and uncover the port 29. A reciprocating movement is imparted to these valves through rock shafts 40 and 41, to 70 which are fixed the rock arms 42 and 43, these latter being connected with the valves through the links 44 and 45. Gravity will hold these valves upon their seat, but if it is desired to positively prevent them from shifting their parallel position thereon, any simple means may be provided that will accomplish this result. One form of such means is illustrated, and consists in the guide rods 86 that are held in a fixed position and 80 project through the lugs 46 upon the valves 38 and 39. By this mechanism the valves are always held in a proper position, laterally and upon their contact surface.

The gas inlet chamber 24 is connected with the gas chamber 22 by the port 47 and the air inlet chamber 25 by the port 48. These ports 47 and 48 are respectively covered and uncovered by valves 49 and 50 which are hinged upon the arms 51 and 52 upon the 95 rock shafts 53 and 54, and are moved toward and away from the valve seat in a rotary path as these shafts move about their axes.

Fixed to the rock shaft 9 is an arm 56 and to the rock shaft 54 an arm 57, and these are 100 connected by a link 58 so that movement of the shaft 9 is transmitted to the shaft 54. Similar mechanism imparts movement to the shaft 53, an arm 59 being fixed to the rock shaft 10, an arm 60 to the rock shaft 53, and 105 a link 61 connecting the outer ends of both of said arms.

Connecting the arms 62 and 63, respectively fixed to the rock shafts 9 and 10, is the spring 64, which exerts a uniform and 110 equal pressure in one direction upon both of the shafts 9 and 10 for a purpose herein-after to be described.

Journalized in the fixed lugs 65 is a rock shaft 66, which is actuated from the rock 115 shaft 11 through the arms 67 and 68, joined by the link 69. The link 69 and arm 67 are pivotally connected by a swivel pin 70 rotatably mounted in the arm 67 and having a stud 71 projecting therethrough, to which 120 is secured one end of the spring 72, the other end being secured to a lug 73 on the body member 1. This spring always exerts its tension so as to move the rock shaft 11 in a direction that will impart a compression action to the diaphragm in the vacuum chamber 6.

Motion is transmitted to the rock shaft 40 from the rock shaft 66 through the arm 74 fixed to the shaft 66, the sector arm 75 fixed 130

to the shaft 40 and the link 76 between said arms. The arm 75 is provided with a slot 77 within which slides the stud 78 that provides means for connecting the link 76 therewith. A screw 79 is rotatably mounted in the block 80 pivotally secured to the sector arm 75 and is threaded through the stud 78, being rotated by the thumb nut 81. By this mechanism means is provided for varying the relative point of connection between the link 76 and arm 75 so as to vary the length of movement of the rock shaft 40 and thus provide means for varying the length of stroke of the valve 38.

15 The rock shaft 41 is actuated from the shaft 66 through the link 82 that is secured at one end to the arm 83 upon the said shaft 41 and at the other end to the arm 84 on the shaft 66, said link being provided at 20 one end with nuts 85 threaded thereon so as to vary the length of said link and thus provide a relative adjustment of the parts.

25 The ports 28 and 29 are shown as triangular in shape and by reason thereof only open gradually, thus producing a more perfect operation of the mechanisms. So far as at present advised, I am the first to use a triangular port in a device of this character, and while the device might operate to advantage with a port of a different shape, yet 30 I am of the opinion that a triangular port is more desirable.

Now, in describing the operation of the mechanism, we will assume that all of the 35 ports are closed and the parts are in the same relative position that they occupy in Fig. 2 with air at atmospheric or other pressure, being within the chamber 25, a source of gas supply at any pressure within the gas 40 chamber 24, no mixture of the air and gas is taking place, no product is passing from the apparatus, and all of the mechanism is at rest. It is the practice to facilitate the distribution of the product by a suction 45 pump which is fixed in the conductor pipe somewhere between the apparatus and the point of consumption, which pump and its method of operation are common in the art and of course are not herein shown. Gas is 50 admitted through the branch 30 and fills the chamber 24 and air is admitted through the branch 31 into the chamber 25, and both of these chambers are filled under pressures 55 having no relation to each other and may be varied as conditions change. The air and gas united into the desired mixture, and as a finished product, passes out through the chamber 23 and neck 26 into a pipe which conducts it to the point of consumption. 60 Immediately the supply is turned on at any point of consumption, the mixture in the exhaust chamber passes therethrough and creates a vacuum within the chamber 23, which is transmitted through the pipes 32 into 65 the vacuum chamber 6 and the diaphragm

therein immediately begins to expand. This expansion causes a rocking movement of the shaft 11, which is transmitted to the valves 38 and 39 through the rock shafts 66, 40 and 41, and said valves begin to slide upon their seat and uncover the ports 28 and 29. This vacuum then passes through said ports 28 and 29 into the chambers 21 and 22 through the pipes 33 and 37 into the chambers 4 and 5. At this time the diaphragms in each of

70 the chambers 4 and 5 begin to expand, causing the shafts 9 and 10 to rotate and thereby lift the valves 49 and 50 off their seat and admit gas and air respectively from the

gas inlet chamber 24 into the gas chamber 22 80 and from the air inlet chamber 25 into the air chamber 21, which then pass respectively

through the ports 28 and 29 and unite in the chamber 23 in the same proportions as the

uncovered portions of the ports 28 and 29 85 bear to each other. This mixture is then

drawn through the neck portion 26 by the

suction in the conductor pipe and passes

on to the point of consumption. Variation

90 in the extent of movement of the valves 38

and 39 determines the extent of the opening

of the ports 28 and 29 and thereby de-

termines the relative proportion of air and

gas in the mixture, and this relative extent

of opening is varied by manipulation of the

95 screw 79 through the thumb nut 81 which

shifts the position of the stud 78 within the

arm 75 and thus varies the length of stroke

of the valve 38. In this construction it will

be observed that the proportioning valves

100 38 and 39 are operated by the diaphragms

within the chamber 6 and that the valves to

admit gas and air are separately operated

by a single diaphragm within the chambers

4 and 5 respectively, thus leaving the air

and gas diaphragms burdened only with a

single valve, thereby placing no undue or

105 differential burden upon either diaphragm.

The air entering through port 48 and gas through port 47 into chambers 21 and 22 respectively, are at a balanced pressure, by reason of the action of the diaphragms in chambers 4 and 5, which operate valves 49 and 50 covering said ports. Therefore the amount of gas and air that passes through 110 the triangular ports 28 and 29 must be in exact proportion to their relative exposed areas.

There are minor changes and alterations 115 that can be made within my invention, aside from those herein suggested, and I would therefore have it understood, that I do not limit myself to the exact construction herein shown and described, but claim all that falls fairly within the spirit and scope of my 120 invention.

Having described my invention, what I claim as new, and desire to secure by Letters Patent, is:-

1. In an apparatus of the character de- 125

130

scribed, the combination with a body member, having separate air and gas inlets and an exhaust outlet; of means, within said body member, for mixing in predetermined proportions the air and gas that passes through said inlets, irrespective of the relative pressure under which the air and gas enter said body member and delivering said mixture to said exhaust outlet; and means for varying such predetermined proportions.

2. In an apparatus of the character described, the combination with a body member, having separate air and gas inlets and an exhaust outlet; of means, within said body member for mixing in predetermined proportions the air and gas that passes through said inlets, irrespective of the relative pressure under which the air and gas enter said body member and delivering said mixture to said exhaust outlet, and maintaining the same at said exhaust outlet in the same relative proportion; and means for varying such predetermined proportions.

3. In an apparatus of the character described, the combination with means for independently receiving air and gas at varying and different pressures, with means for separately reducing said air and gas to a pressure less than atmospheric pressure; means for holding said air and gas balanced at the same pressure; means for uniting the air and gas into a common mixture and in predetermined proportions; and means for varying such predetermined proportions.

4. In an apparatus of the character described, the combination with a body member, having a vacuum chamber, a gas chamber, and an air chamber therein; of a gallery member, having an air chamber, a gas chamber and a vacuum chamber therein; means for connecting both of said vacuum chambers; means for connecting both of said air chambers; means for connecting both of said gas chambers; valve controlled means for admitting air into the air chamber in said gallery member; means for admitting gas into the gas chamber in said gallery member; a port connecting each of said gas and air chambers in said gallery member with the vacuum chamber therein; a valve for covering and uncovering said port; and means, controlled by the diaphragm within the vacuum chamber within said body member for operating said valves.

5. In an apparatus of the character described, the combination with a body member, having a plurality of chamber therein; a diaphragm in each of said chambers; a gallery member, having a plurality of chambers therein, and connected with said body member; valve means for controlling the flow of air into one of the chambers in said gallery member; means for operatively con-

nnecting said valve means with one of said diaphragms; valve means for controlling the flow of gas into one of the chambers in said gallery member; means for operatively connecting the last mentioned valve means with another of said diaphragms; a plurality of valves for controlling the flow of air and gas from said chambers into another chamber in said gallery member; and means, operatively connected with another of said diaphragms for actuating all of said latter valves.

6. In an apparatus of the character described, the combination with a body member, having a vacuum chamber, a gas chamber, and an air chamber therein; of a gallery member, having an air chamber, a gas chamber and a vacuum chamber therein; means for connecting both of said vacuum chambers; means for connecting both of said air chambers; means for connecting both of said gas chambers; valve controlled means for admitting air into the air chamber in said gallery member; means for admitting gas into the gas chamber in said gallery member; a port connecting each of said gas and air chambers in said gallery member with the vacuum chamber therein; a valve for covering and uncovering said port; and means, controlled by the diaphragm within the vacuum chamber within said body member for operating said valves, all of said valves being primarily controlled by the suction within said vacuum chamber.

7. In an apparatus of the character described, the combination with a containing member having a plurality of chambers therein, an air inlet connection into one of said chambers, a gas inlet connection into another of said chambers, a vacuum chamber having connection with both of the aforesaid chambers, a plurality of air filled diaphragms, valves for opening and closing the connection between some of said chambers, the movement of said valves and the admission of air and gas to the apparatus being primarily controlled by the suction within said vacuum chamber.

8. In an apparatus of the character described, the combination with a containing member, having separate air and gas inlets and an exhaust outlet; of diaphragm actuated means for controlling the flow of air and gas in said containing member; diaphragm means for mixing in predetermined proportions the air and gas that pass through said inlets, irrespective of the relative pressure under which the air and gas enter said containing member, and deliver said mixture to said exhaust outlet, said latter diaphragm actuated means being separated from said first mentioned diaphragm actuated means; and means for varying such predetermined proportions.

9. In an apparatus of the character de-

scribed, the combination with a containing member, having separate air and gas inlets and an exhaust outlet; of diaphragm actuated means for mixing in predetermined proportions the air and gas that pass through said inlets, irrespective of the relative pressure under which the air and gas enter said body member and delivering said mixture to said exhaust outlet, and maintaining the same at said exhaust outlet in the same relative proportion; and diaphragm operated means for varying such predetermined proportions, said latter diaphragm means being separate and independent from the first mentioned diaphragm means.

10. In an apparatus of the character described, the combination with a body member, having therein an air chamber, a gas chamber and a vacuum chamber; of a gallery member connected therewith, having an air inlet chamber, an air chamber, a gas inlet chamber, a gas chamber and a vacuum chamber; a diaphragm in each of the three first mentioned chambers; a port connection 20 between both of said air chambers; a port connection between both of said gas chambers; a port connection between the air inlet chamber and air chamber in said gallery member; a port connection between said 25 30 gas inlet chamber and gas chamber in said gallery member; valves for closing both of said latter ports, each being actuated by a diaphragm within one of the chambers in said body member; a port connection between the air chamber in said gallery member and said vacuum chamber; a port connection between said gas chamber in said gallery member and the vacuum chamber 35 40 45 therein; a valve movable in relation to said latter ports to cover and uncover the same; and means for actuating both of said valves from a single diaphragm in one of the chambers in said body member, said diaphragm being independent and separate from the aforesaid diaphragms.

11. In an apparatus of the character described, the combination with a body member, having therein an air chamber, a gas chamber and a vacuum chamber; of a gallery member connected therewith, having an air inlet chamber, an air chamber, a gas inlet chamber, a gas chamber and a vacuum chamber; a diaphragm in each of the three first mentioned chambers; a port connection between both of said air chambers; a port connection between both of said gas chambers; a port connection between the air inlet chamber and air chamber in said gallery member; a port connection between said gas inlet chamber and gas chamber in said gallery member; valves for closing both of said latter ports, each being actuated by a diaphragm within one of the chambers in said body member, said valves being independently movable in a rotary path; a port con-

nection between the air chamber in said gallery member and said vacuum chamber; a port connection between said gas chamber in said gallery member and the vacuum chamber therein; a valve movable in relation to said latter ports to cover and uncover the same; and means for actuating both of said valves from a single diaphragm in one of the chambers in said body member, said diaphragm being independent and separate from the aforesaid diaphragms. 70 75

12. In an apparatus of the character described, the combination with a body member, having therein an air chamber, a gas chamber and a vacuum chamber; of a gallery member connected therewith, having an air inlet chamber, an air chamber, a gas inlet chamber, a gas chamber and a vacuum chamber; a diaphragm in each of the three first mentioned chambers; a port connection between both of said air chambers; a port connection between both of said gas chambers; a port connection between the air inlet chamber and air chamber in said gallery member; a port connection between said gas inlet chamber and gas chamber in said gallery member; valves for closing both of said latter ports, each being actuated by a diaphragm within one of the chambers in said body member; a port connection between the air chamber in said gallery member and said vacuum chamber; a port connection between said gas chamber in said gallery member and the vacuum chamber therein; a valve movable in relation to said latter ports to cover and uncover the same; means for actuating both of said valves from a single diaphragm in one of the chambers in said body member, said diaphragm being independent and separate from the aforesaid diaphragms; and means for varying the relative length of movement of each of said latter valves.

13. In an apparatus of the character described, the combination with a body member, having therein an air chamber, a gas chamber and a vacuum chamber; of a gallery member connected therewith, having an air inlet chamber, an air chamber, a gas inlet chamber, a gas chamber and a vacuum chamber; a diaphragm in each of the three first mentioned chambers; a port connection between both of said air chambers; a port connection between both of said gas chambers; a port connection between the air inlet chamber and air chamber in said gallery member; a port connection between said gas inlet chamber and gas chamber in said gallery member; valves for closing both of said latter ports, each being actuated by a diaphragm within one of the chambers in said body member, said valves being mounted upon independent rock shafts; a port connection between the air chamber in said gallery member and said vacuum chamber; a 110
115
120
125
130

port connection between said gas chamber in said gallery member and the vacuum chamber therein; a valve movable in relation to said latter ports to cover and uncover the same; means for actuating both of said valves from a single diaphragm in one of the chambers in said body member, said diaphragm being independent and separate from the aforesaid diaphragms; and 10 a connection between one of the diaphragms in one of the chambers in said body member with said rock shafts, whereby the expansion or contraction of said diaphragm will impart movement to said rock shaft about 15 its axis.

14. In an apparatus of the character described, the combination with a body member, having therein an air chamber, a gas chamber and a vacuum chamber; of a gallery member connected therewith, having an air inlet chamber, an air chamber, a gas inlet chamber, a gas chamber and a vacuum chamber; a diaphragm in each of the three first mentioned chambers; a port connection 20 between both of said air chambers; a port connection 25 between both of said gas chambers; a port connection between the air inlet chamber and air chamber in said gallery member; a port connection between said gas 30 inlet chamber and gas chamber in said gallery member; valves for closing both of said latter ports, each being actuated by a diaphragm within one of the chambers in said body member; a port connection between 35 the air chamber in said gallery member and said vacuum chamber; a port connection between said gas chamber in said gallery member and the vacuum chamber therein; a valve movable in relation to said latter ports to 40 cover and uncover the same; means for actuating both of said valves from a single diaphragm in one of the chambers in said body member, said diaphragm being independent and separate from the aforesaid 45 diaphragms; and means for simultaneously exerting a uniform compression action upon the diaphragms in the air and gas chambers of said body member.

15. In an apparatus of the character described, the combination with a body member, having therein an air chamber, a gas chamber and a vacuum chamber; of a gallery member connected therewith, having an air inlet chamber, an air chamber, a gas inlet 55 chamber, a gas chamber and a vacuum chamber; a diaphragm in each of the three first mentioned chambers; a port connection between both of said air chambers; a port connection between both of said gas chambers; a port connection 60 between the air inlet chamber and air chamber in said gallery member; a port connection between said gas inlet chamber and gas chamber in said gallery member; valves for closing both of said latter ports, each being actuated by a di-

phragm within one of the chambers in said body member; a port connection between the air chamber in said gallery member and said vacuum chamber; a port connection between said gas chamber in said gallery member and the vacuum chamber therein; a valve movable in relation to said latter ports to cover and uncover the same; means for actuating both of said valves from a single diaphragm in one of the chambers in said body member, said diaphragm being independent and separate from the aforesaid diaphragms; and yielding means for imparting a compression action to the diaphragm in the vacuum chamber of said body member.

16. In an apparatus of the character described, the combination with a containing member having a vacuum chamber therein; of a gallery member having a gas chamber; an air chamber and a vacuum chamber therein; a connection between said vacuum chambers; a port connection between said gas chamber and the vacuum chamber in said gallery member; a port connection between said air chamber and the vacuum chamber in said gallery member; and means for covering and uncovering said ports at one and the same time so as to expose a predetermined area thereof, whereby air passing from said air chamber into said vacuum chamber and gas from said gas chamber into said vacuum chamber will enter said vacuum chamber in relative predetermined proportions.

17. In an apparatus of the character described, the combination with a containing member having a vacuum chamber therein; of a gallery member having a gas chamber, an air chamber and a vacuum chamber therein; a connection between said vacuum chambers; a port connection between said gas chamber and the vacuum chamber in said gallery member; a port connection between said air chamber and the vacuum chamber in said gallery member; means for covering and uncovering said ports at one and the same time so as to expose a predetermined area thereof, whereby air passing from said air chamber into said vacuum chamber and gas from said gas chamber into said vacuum chamber will enter said vacuum chamber in relative predetermined proportions; a diaphragm within the vacuum chamber within said containing member; and means for actuating said valves through an operative connection with said diaphragm.

18. In an apparatus of the character described, the combination with a containing member having a vacuum chamber therein; of a gallery member having a gas chamber, an air chamber and a vacuum chamber therein; a connection between said vacuum chambers; a port connection between said gas chamber and the vacuum chamber in

said gallery member; a port connection between said air chamber and the vacuum chamber in said gallery member; means for covering and uncovering said ports at one and the same time so as to expose a predetermined area thereof, whereby air passing from said air chamber into said vacuum chamber and gas from said gas chamber into said vacuum chamber will enter said 5 vacuum chamber in relative predetermined proportions; a diaphragm within the vacuum chamber within said containing member; means for actuating said valves through an operative connection with said diaphragm; and means for adjusting the relative position of said valves, whereby the relative extent of exposed area of said ports may be varied.

19. In an apparatus of the character described, the combination with a containing member having a vacuum chamber therein; of a gallery member having a gas chamber, an air chamber and a vacuum chamber therein; a connection between said vacuum 25 chambers; a port connection between said

gas chamber and the vacuum chamber in said gallery member; a port connection between said air chamber and the vacuum chamber in said gallery member; means for covering and uncovering said ports at one 30 and the same time so as to expose a predetermined area thereof, whereby air passing from said air chamber into said vacuum chamber and gas from said gas chamber into said vacuum chamber will enter said 35 vacuum chamber in relative predetermined proportions; a diaphragm within the vacuum chamber within said containing member; means for actuating said valves through an operative connection with said diaphragm; and means for adjusting the relative position of said valves, whereby such relative proportions may be varied, said latter means providing for the variation in the length of the stroke of said 40 valves.

In testimony whereof I have hereunto affixed my signature.

EDWIN A. REEVES.
